E. S. Drake

UNITED STATES PATENT OFFICE.

GEORGE F. PASHLEY, OF BROOKLYN, NEW YORK, ASSIGNOR TO HIMSELF
AND BENNETT B. SCHNEIDER, OF ORANGE, NEW JERSEY.

SHADE FOR LAMPS.

SPECIFICATION forming part of Letters Patent No. 236,175, dated January 4, 1881.

Application filed September 16, 1880. (No model.)

To all whom it may concern:

Be it known that I, GEORGE F. PASHLEY, in the city of Brooklyn, county of Kings, and State of New York, have invented certain new and useful Improvements in Shades for Lamps; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention relates to that class of lamp-shades in which the shade entirely surrounds the flame, and has for its object the more efficient protection of the eyes from the direct rays of light radiated from the flame by an increase in the shading ability of the shade, and also an increased stability in position when the lamp upon which the shade is used is moved about.

In the accompanying drawings, Figures 1, 2, 3, 4, and 5 show elevations in outline of my improved shade in some of the various forms in which it may be made. Fig. 6 shows an elevation of a lamp with a burner thereon, and a vertical section of such a shade-holder as is described in the patent of C. Votti, October 3, 1876, with a vertical section of my shade in place thereon. Fig. 7 shows the same view of a lamp and burner as Fig. 6, with a sectional view of a brass shade-ring resting upon the burner outside of the chimney and supporting my improved shade.

Similar letters of reference denote similar parts in each of the figures.

A denotes the body of the shade; B, the neck; C, the lower portion, or what I will, for convenience, call the "canopy." D denotes a horizontal annular portion extending outward from the body A, connecting with the canopy C by a vertical annular portion or ring, D'. E denotes a shade-support. F denotes a lamp, and G a lamp-chimney.

The form of the shade may be varied according to the fancy of the manufacturer. The neck B and the vertical annular ring D' may be omitted, as shown in Fig. 5, without chang-

ing the character of the shade or interfering with its operation.

The essence of the invention is, substantially, making a shade which is in one entire piece, but comprising within itself the features of two separate and entire shades, and in use performs their functions. This is done by providing at the point of junction a device by means of which the shade may rest upon a shade-support, and resting at a point above its center of gravity is more secure.

In Fig. 6 I have shown my improved shade combined with a transparent shade-holder, E, such as I have referred to as described in the patent to C. Votti. When used in this combination the annular horizontal portion D of the shade rests upon the upwardly-extending lip of the shade-holder E and the downwardly-extending portion D' of the shade surrounds the upwardly-extending lip of the shade-holder E, thus preventing lateral motion or displacement.

In Fig. 7 the letter E designates a shade-support of a different kind from that shown in Fig. 6, it being a brass shade-holder consisting of a large ring fitting within the shade at D and D' and connected by wire arms with a ring encircling the burner outside the chimney.

It will be seen that when used in either combination the same advantages result, so far as the extension of the canopy downward to protect the eyes and the additional stability of the shade in its place by the lowering of its center of gravity are concerned.

Previous to my invention there was no shade that provided for the protection of the eyes when transparent shade-holders were used, as the lower part of the shade sat within the lip of the shade-holder, and great annoyance was experienced in the use of such devices upon table-lamps because of the glare of light in the eyes of persons sitting by.

My shade can also be applied to hanging-lamps in the same manner when it is desired to reflect downward a larger proportion of the light.

Having fully described my invention and the manner in which it may be combined and

applied, what I claim as my invention, and desire to secure by Letters Patent, is—

1. A shade constructed substantially as shown, having the body A, the neck B, and the canopy C, with a provision at their point of junction for the combination of the device with a shade holder or support.
2. The combination of a shade constructed substantially as shown and described, having the body A, the neck B, and the canopy C, with a provision at their point of junction for the combination of the device with a shade holder or support, and a shade holder or support, substantially as described.

3. A shade consisting of the body A, neck B, horizontal annular portion D, vertical annular portion D', and canopy C, substantially as described.

4. The combination of a shade consisting of the body A, neck B, horizontal annular portion D, vertical annular portion D', and canopy C, with a shade holder or support, substantially as shown and described.

GEORGE F. PASHLEY.
